ELECTRIC COOKING VESSEL

Melvin H. Boldt, Glenview, Ill., assignor to National Presto Industries, Inc., Eau Claire, Wis., a corporation of Wisconsin

Application August 6, 1956, Serial No. 42,502

Term of patent 14 years

(Cl. D81—10)

Figure 1 is an elevational view of an electric cooking vessel showing my new design;

Figure 2 is a top plan view thereof; and

Figure 3 is a further elevational view thereof taken from the right hand side of Figure 1; and

Figure 4 is an elevational view thereof taken from the left hand side of Figure 1.

The dominant feature of the design resides in those portions shown in full lines.

I claim:

The ornamental design for an electrical cooking vessel, substantially as shown and described.
